UNITED STATES PATENT OFFICE.

JULIUS PEGEL, OF PHILADELPHIA, PENNSYLVANIA, ASSIGNOR TO JOHN BROMLEY & SONS.

DESIGN FOR A RUG.

SPECIFICATION forming part of Design No. 20,372, dated December 9, 1890.

Application filed August 30, 1890. Serial No. 363,561. Term of patent 3½ years.

To all whom it may concern:

Be it known that I, JULIUS PEGEL, a subject of the Emperor of Germany, residing in the city of Philadelphia, State of Pennsylvania, have invented and produced a new and original Design for a Rug, of which the following is a full, clear, and exact description, reference being had to the accompanying drawing, forming a part of this specification.

My invention has relation to the surface ornamentation of a rug; and it consists of the design therefor shown in the accompanying photographic illustration hereto annexed, to which reference is made.

The leading and distinguishing features of the design are the flower-border A, which surrounds the open field center, and the ornamental center piece, consisting of the flower figures B and C within the oval scalloped lines.

I claim as my invention—

1. The design for a rug, substantially as shown and set forth.
2. The design for a border A of a rug, substantially as shown and set forth.
3. The design for the center piece B and C of a rug, substantially as shown and set forth.

In testimony whereof I have hereunto affixed my signature this 31st day of July, A. D. 1890.

JULIUS PEGEL.
